UNITED STATES PATENT OFFICE

2,434,624

PERFORATOR FOR PRINTING PRESSES

Henning E. Peterson, Duluth, Minn.

Application May 16, 1946, Serial No. 670,233

2 Claims. (Cl. 164—100)

1

This invention relates to perforating mechanisms, for printing presses, and has special reference to such a device for cylinder presses, the principal object being to produce a practical, simple, and readily adjustable means for such purpose.

Another object is to provide such a device whereby the perforating process is accomplished at the time the work is passing through the press, thus avoiding the necessity of subsequent action to accomplish same.

Other objects and advantages of the invention will appear in the following description thereof.

Referring now to the accompanying drawing, forming part of this application, and wherein like reference characters indicate like parts:

Figure 1 is a fragmental perspective of the cylinder of an ordinary printing press showing one embodiment of the invention as applied thereto.

Figure 2 is a similar perspective view, somewhat reduced, of the power supplying mechanism for the perforating device at one end of the cylinder of the press.

Figure 3 is an enlarged vertical central section through the perforating disc.

1 represents the cylinder of the press, such as is found upon what is known in the trade as a Miehle cylinder press, and 2 is the driving gear or pinion at one end of the cylinder, and 3 is what is known as the intertape sleeve gear, and it is from this gear that I have shown this embodiment of my invention as being intermittently operated.

At 4 is illustrated a portion of the press frame extending outwardly from the main portion thereof, and there is a similar extension at the opposite end of the cylinder of the press and it is upon these extensions that the perforating frame mechanism is pivotally supported; one of the readily adjustable holding bolts of such attachment being illustrated at 5 so that the perforating frame may be tipped forwardly for the operating gears thereof to engage the constantly rotating sleeve gear 3 or swung therefrom when the perforating device is not in operation.

The perforator frame comprises the end bracket 6, of which there are two though only one is shown, and the upper ends of which are united as by the frame bar 7, and below which, within the frame, are mounted the two shafts 8 and 9, disposed parallel with and above the cylinder 1 of the press, the shaft 8 being for the support of the perforating arm 10, and the shaft 9 being for the driving of the perforating mechanism which will be described later.

2

At the power end of the perforator frame the bracket 6 is illustrated as having associated therewith the upright member 11 having extensions 12 and 13 at opposite ends thereof for the support of the shaft 14 in transmitting power to the shaft 9, and which includes the set of beveled gears 15 keyed to the protruding end of the shaft 9, and the gear 16 on the shaft 14 at the upper end thereof, while a similar pair of bevel gears 17 and 18 are carried at the lower extremity of this portion of the perforator frame. The bevel gear 18 has fixed thereto the spur gear 19 which is for selective engagement with the sleeve gear 3 of the press, though obviously this power transmitting arrangement of gears or other devices may differ materially from that shown without in any way departing from the spirit of the invention.

As previously stated the perforator arm 10 is carried upon the rockable shaft 8 and is adjustable longitudinally thereupon to any position desired as by manipulating of the clamping bolt 20, and the shaft 8 is made rockable so that the perforating disc may be readily adjusted to accommodate the requirements of the work being done. For automatically throwing the perforating disc in or out of action, I have provided at the opposite end of the cylinder 1 to that just described as the power end, means for accomplishing same which embodies the rocker arm 21, keyed to the shaft 8, and extending somewhat beyond the end of the cylinder. This rocker arm 21, carries the roller 22 upon the free end thereof, which roller is operable up and down as by engagement with the gauge block 23, adjustably held within the holding member embodying the bracket like frame 24 and the clamp 25. It will be understood that this holding member is of eccentric construction in respect to the cylinder 1 for the reason that the cylinder in this type of printing press is intermittently raised and lowered during the printing process, therefore the necessity of the holding member just described being of eccentric construction in relation to the end of the cylinder and adjustably mounted thereupon to suit circumstances as by the bolts 26 so that the same may be set to compensate for the reciprocal action of the cylinder. Furthermore the block 23 may be of any desired number, or different lengthened ones may be kept in stock for ready application within the holding member or positioned therein to bring the perforating disc out of and into action at the proper time as the job on the press may require; it being plainly illustrated that the clamping member 25 is read-

ily adjustable as by wing nuts indicated at 27. Thus it is readily seen that the perforating disc indicated at 28 is readily automatically controlled.

The perforating wheel may be of any desired type, though I have illustrated same as being of two like halves 28—29, mounted upon the sleeve hub 30 of the sheave 31 and having clamped therebetween the toothed disc 32 which performs the perforating act. The sheave 31 is rotatably carried upon the pin 33, mounted within the bifurcated ends of the arm 10, it being screw threaded into the outermost one, as at 34, or otherwise attached as desired, thus providing a simple and convenient journal for the perforating disc. The sheave is operated as by a belt 35 passing therearound at one end and around the shaft 9 at the opposite end for simultaneously rotating the perforating disc with the rotation of the shaft 9 and preferably at the same speed as the cylinder.

This arrangement of perforating disc in conjunction with the cylinder is further novel in that there is disposed intermediate of the disc and the cylinder a slotted shield plate 36, adjustably supported in any desired manner as at 37 upon the cross member 38 of the printing press structure so that it may be adjusted longitudinally of the cylinder when the perforating disc support is adjusted. This shield obviously prevents the teeth of the disc harmfully injuring the make-ready surface of the cylinder, and furthermore insures adequate perforation of the perforating teeth through the sheet being printed, as received from the feedboard 39.

Having thus described my invention, what I claim and desire to secure by Letters Patent, is:

1. In a cylinder printing press having a feed table, two parallel shafts spaced above the cylinder of said press, parallel therewith and spaced forwardly of the forward edge of said table, means for rotating one of said shafts coincident with the rotation of said cylinder, a perforating disc, supported by the other of said shafts, adjustable longitudinally thereof and extending towards the forward edge of said feed table, means for rotating said disc from said rotatable shaft, and an apertured foot plate for cooperative engagement with said disc and adjustable longitudinally of said cylinder.

2. A sheet perforating device for cylinder printing presses comprising in combination two parallel shafts mounted above said cylinder parallel therewith and spaced therefrom, one of said shafts being rotatable, a perforating disc pivotally supported by the other of said shafts above the cylinder of said press, means for rotating said disc from said rotatable shaft at a predetermined speed in relation to the motion of the said press and simultaneously therewith, an apertured plate between said disc and said cylinder to insure against displacement of a sheet being perforated, and means for selectively setting the perforating device for intermittent operation.
